UNITED STATES PATENT OFFICE

CARL A. ISBERG, OF DENVER, COLORADO

DESIGN FOR A CONFECTION

Application filed January 13, 1931. Serial No. 38,296. Term of patent 14 years.

To all whom it may concern:

Be it known that I, CARL A. ISBERG, a citizen of the United States, residing at Denver, in the county of Denver, and State of Colorado, have invented a new, original, and ornamental Design for Confections, of which the following is a specification, reference being had to the accompanying drawing, forming part hereof.

The drawing illustrates a perspective view of my new design.

I claim:

The ornamental design for a confection as shown.

CARL A. ISBERG.
